UNITED STATES PATENT OFFICE.

AUGUSTA WELLS, OF BERKELEY, COLORADO.

DESIGN FOR A MAT FOR PICTURES.

SPECIFICATION forming part of Design No. 25,644, dated June 16, 1896.

Application filed May 7, 1896. Serial No. 590,627. Term of patent 7 years.

To all whom it may concern:

Be it known that I, AUGUSTA WELLS, of Berkeley, in the county of Arapahoe and State of Colorado, have invented and produced a 5 new and original Design for a Mat for Pictures and the Like, of which the following is a full, clear, and exact description.

Reference is to be had to the accompanying drawings, forming a part of this specification, 10 in which—

The leading feature of my design consists of the border of flowers at the opening in the 15 mat, the edge of the mat at the said opening following the lines of the inner edge of the border of flowers.

A minor feature of the design is the said border of flowers appearing in relief. 20

I claim—

The design for a mat herein shown and described.

AUGUSTA WELLS.
